(57) **CLAIM**

The ornamental design for a computer attachment for photographs and information cards, as shown and described.

DESCRIPTION

FIG. 1 is a perspective view of a computer attachment for photographs and information cards showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof; and,

FIG. 7 is a right-side elevational view thereof.

The broken lines are included for the purpose of showing environment and form no part of the claimed design.

1 Claim, 3 Drawing Sheets

FIG. I

FIG. 2**FIG. 3****FIG. 4****FIG. 5**

FIG. 6**FIG. 7**
